LIGHT INDICATOR FOR HEADLIGHTS

Mortimer H. Mellen, Cliftondale, Mass.; Mabel L. Mellen executrix of said Mortimer H. Mellen, deceased

Application January 7, 1933, Serial No. 650,698

7 Claims. (Cl. 240—8.4)

This invention relates to a novel and improved light indicator for application to the headlamp of a vehicle, to indicate to the operator, when he is in the usual driving position, whether or not the headlamp is lighted.

The invention will best be understood by reference to the following description, when taken in connection with the accompanying drawing of one specific embodiment thereof, while its scope will be pointed out more particularly in the appended claims.

In the drawing:

Fig. 1 is a plan of an indicator embodying the invention;

Fig. 2 is a front elevation of the same; and

Fig. 3 is a vertical, sectional view, on line 3—3 of Fig. 2, of the indicator applied to a headlamp.

Referring to the drawing, and to the embodiment of the invention selected for illustration, there is shown in Fig. 3 a portion of a headlamp 5 of known construction, comprising a housing or shell 6, which houses a reflector 7 with which there is associated a light source, such as an incandescent lamp bulb not shown. A bezel 8, suitably secured to the shell is provided with an inwardly-directed, annular flange 9, which holds a lens 10 against a gasket 11, which in turn is seated in an annular groove 12 presented by the reflector. The lens presents at the front an annular shoulder 13 close to the flange 9. It is deemed unnecessary to describe the lamp in further detail, as lamps differ somewhat in construction, especially in respect to the means for fastening the bezel to the shell.

The indicator, as shown, comprises an arcuate member 14, having an arcuate flange 15 for insertion between the lens and the bezel, and an arcuate flange 16, transversely disposed with relation to the flange 15, and projecting forwardly from the lens and the bezel. The juncture of the two flanges rests against the shoulder 13 of the lens, and the arcuate member is thus interlocked with the bezel and the lens, and is prevented from slipping out of its place.

The forwardly-directed flange 16 is provided with an opening 17, herein generally circular, which receives a housing 18, herein dome-shaped, or bulb-shaped, the same being conveniently held in place in the opening, as by being provided with a bead 19 above the opening, and an outwardly-directed flange 20 below the opening. The housing 18 is inserted from above, and the flange 20 formed afterward. While the flange 20 may be squeezed firmly enough against the flange 16 to pinch the latter between the bead 19 and the

flange 20 to prevent the housing 18 from turning about its vertical axis, in the present example, the opening 17, though generally circular, is provided with a flat portion, as at 21, and the housing 18 is similarly shaped at the same point.

5

Light rays emanating from the lamp upwardly through the opening 17 into the interior of the housing 18 are emitted through a rearwardly-directed opening 22 toward the operator. To assist in the transmission of the light rays in the form shown, the indicator comprises a light-transmitting element, herein conveniently in the form of a hollow, dome-shaped glass body 23, which if desired may be colored, and its external form is such that it closely fits the internal surface of the housing 18. The body 23 is conveniently held in place by a resilient split ring 24, which is received in an annular groove 25 presented by the bead 19. This ring fits snugly against the lower edge of the body, and holds the latter firmly in place.

15

The indicator may easily be applied to various standard lamps, and even if there is a variation in the diameters of the lamps, the arcuate body 14, being of rather thin, bendable metal, can be bent to various arcs within reasonable limits. The forwardly-directed flange 16, in addition to affording a support for the housing 18 and body 23, constitutes also a visor which limits upward dispersion of the light rays in a forward direction. A sufficient amount of light passes into the body 23, and is transmitted rearwardly to enable the operator, when in the usual driving position, to see whether or not the headlamp is lighted. A small glowing spot of light will show 30 at the opening 22, at a point somewhat above the top of the lamp.

35

Having thus described one embodiment of the invention, but without limiting myself thereto, what I claim and desire by Letters Patent to 40 secure is:

1. In a light indicator for headlamps, the combination of a member having attaching means for attachment to a headlamp, and a horizontally and forwardly-directed arcuate flange provided with an entrance opening in a horizontal plane, a housing supported by and above the flange and having its interior communicating with said opening, said housing having an exit aperture directed rearwardly toward said attaching means, and a light-transmitting element received within said housing between said opening and said aperture, receiving light rays directly from the head-lamp and transmitting the light rays rearwardly through said exit aperture. 45

50

55

2. In a light indicator for headlamps, the combination of a member having attaching means for attachment to the bezel of a headlamp, an arcuate flange provided with an opening, a housing supported by said flange and having its interior communicating with said opening, said housing being provided with an internal, annular shoulder, and being provided with an aperture directed rearwardly toward said attaching means, a light-transmitting element received within said housing above said shoulder, and retaining means resting on and above said shoulder to retain said element in place.
3. In a light indicator, the combination of an arcuate member provided with an opening, a housing supported by said member and having its interior communicating with said opening to receive light rays from a lamp, a second opening to emit the light rays, said housing being provided with projections at opposite sides, respectively, of said member to retain said housing in place in said opening, one of said projections being a hollow bead presenting an annular groove, a light-transmitting body within said housing and extending across said second opening, and a retaining ring seated in said groove to retain said body in place.
4. In a light indicator for attachment to the front of a headlamp, the combination of attaching means for attachment to a headlamp, a web to extend forwardly from the headlamp, said web being provided with an opening to face inwardly toward the optical axis of the headlamp, a bell-shaped housing having a portion extending through said opening and attached to said web, said housing constituting a chamber provided with a rearwardly directed light exit opening, and a tapered light transmitting element in contact with the interior of said housing and to serve to transmit light rays rearwardly through said light exit opening.
5. In a light indicator for attachment to the front of a headlamp, the combination of attaching means for attachment to a headlamp, a web to extend forwardly from the headlamp, said web being provided with an opening to face inwardly toward the optical axis of the headlamp, a dome-shaped housing having a portion extending through said opening and secured to said web, said housing constituting a chamber provided with a rearwardly directed light exit opening, a dome-shaped light transmitting element in said housing to transmit light rays rearwardly through said light exit opening, and means adjacent the inner end of said housing to hold said light transmitting element in contact with the interior of the housing.
6. In a light indicator for attachment to the front of a headlamp, the combination of attaching means for attachment to a headlamp, a web to extend forwardly from the headlamp, said web being provided with an opening to face inwardly toward the optical axis of the headlamp, a generally conical housing having its base attached to said web and constituting a chamber provided with a rearwardly directed light exit opening, and a generally conical light transmitting element in contact with the interior of said housing and to serve to transmit light rays rearwardly.
7. In a light indicator for attachment to the front of a headlamp, the combination of attaching means for attachment to a headlamp, a web to extend forwardly from the headlamp, said web being provided with an opening in a horizontal plane to receive light rays directed upwardly and forwardly from the front opening of the headlamp, a housing above said web and constituting a chamber having upwardly converging sides and communicating with the space below said opening, said housing having a rearwardly directed exit aperture, and a light-transmitting element having outwardly converging sides in contact with the interior of said chamber and transmitting the light rays to the rear of said aperture.

MORTIMER H. MELLEN.
